(57) **CLAIM**

The ornamental design for a vehicle side mirror, as shown and described.

DESCRIPTION

FIG. 1 is a rear perspective view of a vehicle side mirror showing our new design;

FIG. 2 is a front perspective view thereof;

FIG. 3 is a front elevational view thereof;

FIG. 4 is a side elevational view thereof;

FIG. 5 is a rear elevational view thereof;

FIG. 6 is a rear perspective view of the left-handed version thereof;

FIG. 7 is a front perspective view of the left-handed version thereof;

FIG. 8 is a front elevational view of the left-handed version thereof;

FIG. 9 is a side elevational view of the left-handed version thereof; and,

FIG. 10 is a rear elevational view of the left handed version thereof.

The vehicle side mirror illustrated in FIGS. 1-5 is right-handed, and FIGS. 6-10 illustrate the left-handed version of the mirror having the same design.
